UNITED STATES PATENT OFFICE.

ALFRED F. YARROW, OF BLANEFIELD, SCOTLAND.

WATER-TUBE BOILER.

1,101,606.

Specification of Letters Patent. Patented June 30, 1914.

Application filed January 20, 1912. Serial No. 672,494.

To all whom it may concern:

Be it known that I, ALFRED FERNANDEZ YARROW, a subject of the King of Great Britain, residing in Blanefield, and whose post-office address is Campsie Dene, Blanefield, in the county of Stirling, Scotland, engineer, have invented certain new and useful Improvements in Water-Tube Boilers, of which the following is a specification.

This invention relates to water tube boilers having a steam and water drum which is connected by downwardly extending tubes with hot water and feed water drums or compartments, and the object of the invention is to provide means for preventing the relatively cold water which enters the steam and water drum through the feed heating tubes passing freely or directly to the adjacent generator tubes and thus cooling the water in these tubes and in the water drum or drums with which they are connected, and also preventing the establishment of an independent circulation of water between the steam and water drum and the feed water drum or drums or compartments.

The invention further comprises the provision of means for insuring that the feed heating tubes will be filled with water so long as there is water in the steam and water drum, even should the feed pump break down.

With these objects the steam and water drum is provided with one or more longitudinal partitions or baffles, according to the number of sets of feed heating tubes connected with the steam and water drum, each such partition forming a longitudinal compartment or pocket within the drum opposite the ends of a set of feed heating tubes, and these partitions extend from the lowest of the feed heating tubes approximately to or above the normal water level in the steam drum. The partitions may be solid, or they may have openings which permit of a moderate flow of feed water otherwise than over the top of the partitions. The supplementary or feed water drums in addition to being connected with the steam and water drum by feed heating tubes, are also connected therewith at or about its lowest point by means of a pipe or pipes whereby the feed heating tubes and supplementary or

feed water drums, which are at a lower level than the steam and water drum are kept full or substantially full of water so long as there is any water left in the steam drum.

In the accompanying drawings, Figure 1 is a transverse section of a water tube boiler embodying my invention, and Fig. 2 is a similar view showing a modification of the same.

Referring to Fig. 1 of the drawings, I have shown my invention as applied to a water tube boiler of the Yarrow type (shown in cross section) having a steam and water drum *a* which is connected with two water drums *b*, *b'* (one on each side of the furnace) by two sets of generator tubes *c*, *c'*. As shown in this drawing two supplementary or feed water drums *d*, *d'* are fitted one on each side of the generator tubes and beyond them in the direction of flow of the furnace gases, these feed water drums being connected with the steam and water drum *a* by feed heating tubes *e*, *e'* respectively which enter the steam drum at or above or below the normal water level in the said drum.

Within the steam and water drum *a* are two longitudinal partitions or baffles, *f*, *f'*, one at each side, forming pockets *g*, *g'* respectively which are co-extensive longitudinally with the respective sets of feed heating tubes and which extend vertically from the lowest row of feed heating tubes either approximately to the normal water level in the steam drum, or beyond this level. These plates or baffles *f*, *f'* may, if desired, have openings or perforations which, while permitting a certain flow of water from the feed heating tubes into the body of water in the steam and water drum *a* otherwise than over the upper edges of the baffles, nevertheless prevents any direct or free flow of water from the feed heating tubes *e*, *e'* into the neighboring rows of the generator tubes *c*, *c'* respectively. Further, the supplementary water drums *d*, *d'* may be connected with the steam and water drum *a* at or near its lowest point by means of one or more pipes such as *h*, *h'* whereby the drums *d*, *d'* and the tubes *e*, *e'* may be kept to a greater or less extent full of water, so long as there is any water in the steam drum *a*, the level of the drums *d*, *d'* being arranged sufficiently below the steam drum *a* for this purpose.

A modified construction of boiler of the same type is shown in Fig. 2. In this construction there is shown only one supplementary or feed water drum *d* connected by feed heating tubes *e* with the compartment *g* within the steam drum formed by the partition or baffle *f*. On the other side of the boiler there is fitted a set of steam super-heating tubes *i* which are connected at one end with the steam and water drum *a* at or near its highest point, and at the other end with a steam collector *j*, the uptake of the furnace gases being divided by a longitudinal partition *k* and a damper *m* being fitted on that part of the uptake in which the super-heater *i* is disposed in the manner described in my previous British Patent specification No. 10231 of 1910. It will be understood that in this case also the auxiliary water drum *d* may be connected with the steam and water drum *a* at or near its lowest point by means of an additional pipe or pipes, as and for the purpose described with reference to Fig. 1.

While the auxiliary or feed water drums may be separate, as shown in Figs. 1 and 2, they may alternatively be constituted by a longitudinal partition or partitions *n* in the main water drum or drums *b*, *b'*, as indicated in dotted lines in Fig. 2, such partitions forming a pocket *o* into which the lower ends of the outer rows of the tubes *c* (or *c'*) open and to which the feed water is delivered, so that the said outer rows constitute feed heating tubes.

Having thus described the nature of the said invention and the best means I know of carrying the same into practical effect, I claim:—

1. A water tube boiler having a steam and water drum disposed substantially centrally above the furnace, water drums at a lower level connected by generator tubes with said steam and water drum, there being one of said drums at each side of the furnace, a feed water drum or compartment connected by feed heating tubes with the steam and water drum and disposed beyond the generator tubes in the direction of the flow of the gases at that side of the furnace, at least some of said tubes opening into the steam and water drum below the normal water level therein, and a longitudinal baffle in the steam and water drum, said baffle forming a pocket closed along the lower side into which the feed water heating tubes discharge and communicating with the steam and water drum, said communication being so arranged that the water entering the steam and water drum from the feed water heating tubes is constrained to mix with the mass of water in the steam and water drum and is prevented from passing directly to the adjacent generator tubes, substantially as described.

2. A water tube boiler having a steam and water drum substantially centrally disposed above the furnace, water drums at a lower level connected by generator tubes with said steam and water drum, at least one of said water drums being situated at each side of the furnace, a feed water drum or compartment on one or both sides of the furnace connected by feed heating tubes with the steam and water drum, at least some of said tubes opening into the steam and water drum below the normal water level therein, said compartment or compartments communicating with the water space of the steam and water drum, said feed water heating tubes being disposed beyond the generator tubes in the direction of the flow of gases at that side of the furnace, and a pipe or pipes connecting the feed water drum or drums or compartments with the steam and water drum at or near the lowest point of the same, substantially as described.

3. A water tube boiler having a steam and water drum disposed substantially centrally above the furnace, two or more water drums connected therewith by generator tubes, there being at least one water drum on each side of the furnace, one or more feed water drums or compartments, one or more longitudinal baffles in the steam and water drum forming pockets in the same closed along their lower sides but communicating with the water space thereof, feed water heating tubes connecting the feed water heating drums or compartments with said pockets, at least some of said feed water heating tubes opening into the steam and water drum below the normal water level therein, and pipes connecting the feed water heating drums with the steam and water drum near its lowest point and outside the aforesaid pockets, substantially as described.

4. A water tube boiler having a steam and water drum disposed substantially centrally above the furnace, two or more water drums connected therewith by generator tubes, there being one of said water drums on each side of the furnace, a feed water drum or compartment on one side of the furnace beyond the generator tubes at that side and beyond the direction of the flow of the furnace gases, a longitudinal baffle in the steam and water drum forming a pocket in the same closed along its bottom and side but communicating therewith, feed water heating tubes connecting the feed water heating compartment or drum with said pocket, at least some of said feed water heating tubes communicating with the steam and water drum below the normal water level therein, a pipe connecting the feed water heating drum with the steam and water drum near its lowest point and outside of the aforesaid pocket, a superheater upon one side of the boiler and beyond the generator tubes on

that side of the furnace in the direction of the flow of gases, a flue leading from each side of the furnace, and a damper in the flue leading from the side of the furnace in which the superheater is located for controlling the flow of gases from that side of the furnace, substantially as described.

In testimony whereof I have signed my name to this specification in the presence of two subscribing witnesses.

A. F. YARROW.
